UNITED STATES PATENT OFFICE.

FREDERICK W. SCHOETTLE, OF OAK PARK, ILLINOIS, ASSIGNOR OF ONE-HALF TO
NORMAN B. LEWIS, OF CHICAGO, ILLINOIS.

WATER HEATER.

1,403,645.

Specification of Letters Patent. Patented Jan. 17, 1922.

Application filed June 26, 1918. Serial No. 242,043.

To all whom it may concern:

Be it known that I, FREDERICK W. SCHOETTLE, a citizen of the United States, residing at Oak Park, in the county of Cook 5 and State of Illinois, have invented new and useful Improvements in Water Heaters, of which the following is a specification.

This invention relates to hot water heaters employing a gas burner for the heating medium. The heater is designed more particularly for hot-water heating plants, although it may also be used as a steam generator for steam-heating plants.

The invention has for its object to provide 15 a very simple and efficient heater of the kind stated which can be readily installed and which is capable of being connected to any ordinary coal-burning hot water or steam heating system already installed.

20 The object stated is attained by means of a novel combination and arrangement of parts to be hereinafter described and claimed, and in order that the same may be better understood, reference is had to the 25 accompanying drawings, forming a part of this specification.

In the drawings,

Figure 1 is a vertical section of the heater, and Fig. 2 is a horizontal section on the line 30 2—2 of Fig. 1.

Referring specifically to the drawings 10 denotes a suitable stand supporting a sheet metal or other casing 11. In the upper part of this casing is mounted a water container 12 of cylindrical form, and below the same is located a series of water heating coils 13 which are vertically positioned. These coils are heated by a gas burner, a burner unit 14 being positioned beneath each coil. The 15 coils and burners are also enclosed in the casing 10. The coils are fitted at their bottom by means of pipes 14^a to a supply connection. At the top, the coils are connected to the container 12, each coil being connected by a pipe 15 to a coupling 16 from which latter a pipe extends and is connected to the bottom of the container. From the top of the container extend pipes 17 which connect to the mains that supply the radiators. It 20 may be here stated that the heater is intended for hot water, steam or vapor heating plants. For a hot water heating plant

the container will be kept full, whereas for a steam heating plant it will be kept partly filled to obtain a steam collecting space.

55 Between the top of the coils 13 and the bottom of the water container 12 is located a heat concentrating hood 18 which is dimensioned to extend completely across the inside of the casing 10, and has a flared central outlet 19 at the top to direct the heat 60 against the bottom of the container 12. This hood holds the heat from the burners 14 around the coils 13 so that the water therein is quickly heated.

65 To the top of the casing is connected a draft flue 20 provided with a hood 21 to prevent sudden up or down drafts from extinguishing the burners 14. The flue has two vertically spaced sets of openings 22 and 70 23, respectively, and the hood is mounted on the outside of the flue over these openings. Inside the flue in the plane of the top openings 22, is located a cone 24 which primarily acts to deflect the passage of the 75 draft through the flue. The draft escapes through the bottom openings 23 and passes into the hood 21, and then returns by the way of the top openings 22 into the flue. The cone is principally intended to serve as 80 a baffle, however, to protect the burners 14 from down drafts. In the event of a strong down draft through the flue, the cone deflects the same sidewise through the top openings into the hood, thus preventing the 85 burners 14 from being extinguished.

85 Beneath the inlet end of the flue 20 is a baffle plate 30 which permits the fumes to escape, but prevents the heat accumulating about the container 12 from rising directly 90 into the flue.

I claim:

In a water heater, a casing, a water container located in the casing, a series of vertically positioned heating coils beneath the 95 container and connected thereto, heating burners beneath the coils, and a heat retaining hood in the casing closing up the same between the bottom of the container and the top of the coils, said hood having a top 100 opening located beneath the bottom of the container to direct the heat thereagainst.

In testimony whereof I affix my signature.
FREDERICK W. SCHOETTLE.
